DESIGN FOR A FINGER RING

Herbert J. A. Skipp, East Providence, R. I., assignor to James Perry Mfg. Co., Providence, R. I., a corporation of Rhode Island

Application October 1, 1948, Serial No. 148,930

Term of patent 7 years

(Cl. D45—10)

To all whom it may concern:

Be it known that I, Herbert J. A. Skipp, a citizen of the United States, residing at East Providence, in the county of Providence and State of Rhode Island, have invented a new, original, and ornamental Design for a Finger Ring, of which the following is a specification, reference being had to the accompanying drawing, forming part thereof.

Referring to the drawing:

Fig. 1 is a top plan view showing my new design for a finger ring;

Fig. 2 is a front elevation thereof; and
Fig. 3 is a side elevation thereof.

I claim:

The ornamental design for a finger ring, substantially as shown.

HERBERT J. A. SKIPP.
